UNITED STATES PATENT OFFICE.

CAREY C. FINKHOUSEN, OF WREN, OHIO.

WRENCH.

1,415,826.

Specification of Letters Patent. Patented May 9, 1922.

Application filed January 4, 1922. Serial No. 526,948.

To all whom it may concern:

Be it known that I, CAREY C. FINKHOUSEN, a citizen of the United States, residing at Wren, in the county of Van Wert, State of Ohio, have invented certain new and useful Improvements in Wrenches; and I do hereby declare the following to be a full, clear, and exact description of the invention, such as will enable others skilled in the art to which it appertains to make and use the same.

This invention relates to new and useful improvements in wrenches and particularly to adjustable rigid jaw wrenches.

15 One object of the invention is to provide a wrench of the type having a rotatable head formed with a plurality of nut engageable sockets of different sizes, and means for holding the heads in position to present any 20 one of the sockets to the work.

Another object is to provide a wrench of this character wherein the heads holding means also serves to hold a rotatable screw-driver element carried in the other end of 25 the handle shank.

Other objects and advantages will be apparent from the following description when taken in connection with the accompanying drawings.

30 In the drawing:

Figure 1 is an elevation of a wrench made in accordance with the invention.

Figure 2 is an elevation viewed in a plane at right angles to that of Figure 1.

35 Figure 3 is a vertical longitudinal sectional view on the line 3—3 of Figure 2, just inside of the side of the handle shank.

Figure 4 is a transverse sectional view through the collar and shank, on the line 40 4—4 of Figure 1.

Figure 5 is a perspective view of one of the side plates of the handle showing the modification thereof.

Referring particularly to the accompanying drawing, the handle shank comprises a pair of side members 10, the opposite ends of the members being rounded, as at 11, and centrally apertured, at 12. Between the ends of the members 10 of the handle shank 50 are disposed the members 14 and 15.

The member 14 comprises a circular disk having a plurality of notches or recesses 14' in its periphery for engagement with work, and being of different sizes, as clearly seen 55 in Figure 1. The member 14 is mounted on a central pivot 16, disposed through the

disk and the apertures 12, at that end of the handle.

The member 15 is mounted on a pivot 17 disposed through said member and through the apertures 12, at the other end of the handle. The member 15 is formed with a screw-driver point 18 at each end, and of different sizes, each being arranged to extend beyond the end of the handle, when rotated into the position shown in Figure 1.

Slidable longitudinally on the handle shank is a collar 19, said collar being of such size as to straddle the portion of the head 14, which lies between two adjacent notches 70 or recesses 14', for the purpose of maintaining the head against rotation in the shank, while the tool is in operation. It will be particularly noted that the portions of the member 14, between the recesses 14' are of 75 equal width at their outer ends, and that such width is slightly less than the longer inside dimension of the collar 19, so that when the collar is engaged with any one of the said portions of the head 14, said 80 head will be held against any tendency to rotate.

It will be noted that the wider sides of the collar 19 are bowed inwardly toward the sides of the handle, as shown at 20, to frictionally engage therewith and hold the collar against sliding.

When one or the other of the screw-driver points is extended from the end of the handle, the collar 19 is slipped down to that 90 end of the handle, and in position to close the open sides of the shank, so that the member 15 cannot rotate within the handle while the exposed point is in use, the bowed sides of the collar holding the same from 95 sliding movement on the handle.

In Figure 5 there is shown a modification in the form of the handle, wherein the opposite ends of the side plates are slightly widened, as shown at 21, so that the collar 100 19 will wedge therewith for the purpose of preventing backward sliding movement of the collar, while the tool is being used. When this form of handle is used the collar is provided with parallel sides, the inwardly bowed sides of the first form of collar being unnecessary.

What is claimed is:

1. A tool including a shank, a member rotatable in one end of the shank and having a plurality of notches in its periphery with the outer ends of the portions interme-

diate the notches of substantially equal width, and a collar slidable on the shank and arranged to enter two adjacent notches of the rotatable member to embrace one of said 5 intermediate portions.

2. A tool including a shank, a member rotatable in one end of the shank and having a plurality of notches in its periphery with the outer end of the portions intermediate 10 the notches of substantially equal width, and a collar slidable on the shank and arranged

to embrace one of said intermediate portions, the wider side portions of the collar being bowed inwardly for frictional engagement with the sides of the shank.

In testimony whereof, I affix my signature 15 in the presence of two witnesses.

CAREY C. FINKHOUSEN.

Witnesses:

GEORGE W. DULL,
CLOYD T. CLANTZ.
